UNITED STATES PATENT OFFICE.

WARREN MACPHERSON, OF CAMBRIDGE, MASSACHUSETTS.

RUBBER SHOE-BOTTOM.

1,350,930.

Specification of Letters Patent. Patented Aug. 24, 1920.

Application filed January 26, 1920. Serial No. 353,995.

To all whom it may concern:

Be it known that I, WARREN MACPHERSON, a citizen of the United States, residing at Cambridge, in the county of Middlesex 5 and State of Massachusetts, have invented new and useful Improvements in Rubber Shoe-Bottoms, of which the following is a specification.

This invention relates to a rubber shoe bottom comprising a rubber sole having a fore portion, a shank portion, and a heel portion, and a rubber heel body associated with the heel portion and united thereto, the entire bottom being adapted to be attached as one part to a boot or shoe, and forming the entire tread portion of the latter.

The object of the invention is to enable the rubber heel body to be stripped from the heel portion of the sole, when the heel body has been rendered useless by wear, so that an unworn heel body may be substituted for one which is worn out.

The invention is embodied in the improvements which I will now proceed to describe and claim.

Of the accompanying drawings forming a part of this specification,—

Figure 1 is a view of the under side of a shoe bottom embodying the invention.

Fig. 2 is a section on line 2—2 of Fig. 1.

Fig. 3 is a view similar to Fig. 2, showing the heel body after it has been reduced by wear.

Fig. 4 is a sectional view of the heel portion of the sole after the heel body has been stripped therefrom.

The same reference characters indicate the same parts in all of the figures.

In the drawings, 12 represents the fore portion, 13 the shank portion, and 14 the heel portion of a rubber sole molded in one piece. 15 represents a rubber heel body associated with the heel portion 14, and provided with the usual sockets 16 and metal washers 17, permitting the attachment of the heel body and heel portion 14 to a boot or shoe by the usual attaching nails.

In carrying out my invention, I interpose between the heel portion 14 and body 15 a layer 18 of relatively weak material, such as textile fabric or paper, said layer being united to the proximate surface of the heel

portion and body, and forming a rupturable connection therebetween, so that the body 55 15 may be stripped from the heel portion 14 to permit a new heel body to be substituted for one which has been reduced by wear.

In practice the heel body 15 is preferably formed in a suitable mold, from unvulcanized rubber, the layer 18 is placed upon the upper surface of the body 15 before vulcanization, and the heel portion 14 is placed upon the layer 18, also before vulcanizing, the parts being contained in a suitable vulcanizing mold and subjected to vulcanizing heat. The heel portion 14 and heel body 15 are united to the layer 18 by the vulcanizing operation.

When the body 15 has been reduced by 70 wear, as indicated by Fig. 3, the attaching nails may be removed and the remnant of the body 15 may then be stripped from the heel portion 14, leaving the latter in the condition shown by Fig. 4, so that a new 75 body 15 may be subsequently secured to the heel portion by any suitable means, such as cement or by a set of attaching nails, or both.

It will be seen that the layer 18 covers the 80 under surface of the heel portion 14, and has a curved edge portion registering with the curved margin of the heel portion, and a breast edge portion extending across the bottom of the rubber sole. It will also be 85 seen that the curved edge portion and the breast edge portion of the rubber heel body 15 register respectively, with the curved edge portion and the breast edge portion of the layer 18, so that when the heel 90 body is stripped from the heel portion 14, a seat is left on the latter, as shown by Fig. 4, to which another duplicate heel body may be applied.

I claim:

A shoe bottom attachable as a single part to a shoe, and comprising a rubber sole formed as a single integral part, and including a fore portion, a shank portion, and a heel portion, a layer of rupturable material covering the under surface of the heel portion and having a curved edge portion registering with the curved margin of the heel portion, and a breast edge portion extending across the bottom of the sole, and a 100 rubber heel body, the curved edge portion 105

and breast edge portion of which register respectively with the curved edge portion and the breast edge portion of the said layer, said heel body being provided with means for engaging attaching nails, the said heel portion, layer, and heel body being united by vulcanization, and the heel body being

adapted to be stripped from the heel portion to leave on the latter a seat to which another duplicate heel body may be applied. ¹⁰

In testimony whereof I have affixed my signature.

WARREN MacPHERSON.
